4 Sheets-Sheet 2

The drawing shows a top-down view of a rectangular frame assembly. The frame is supported by a central vertical post labeled 30. The top edge of the frame has a decorative border. On the top surface, there is a rectangular panel with a central circular hole. A small rectangular component labeled 16 is positioned above the hole. Two small rectangular components labeled 15 are attached to the top edge of the panel. Two small rectangular components labeled 13 are attached to the bottom edge of the panel. Two small rectangular components labeled 14 are attached to the left and right edges of the panel. The left and right edges of the frame have vertical supports labeled 29. The top and bottom edges of the frame have vertical supports labeled 29'. The right side of the frame has a vertical support labeled 35. The top and bottom edges of the frame have vertical supports labeled 35'. The left side of the frame has a vertical support labeled 36. The right side of the frame has a vertical support labeled 46. The top edge of the frame has a vertical support labeled 46'. The bottom edge of the frame has a vertical support labeled 36'. The central vertical post is labeled 30. The left side of the post is labeled 31. The right side of the post is labeled 32. The top of the post is labeled 6. The bottom of the post is labeled 7. The drawing is labeled 'Fig. 2.' in the top left corner, 'Fig. 1.' in the bottom right corner, and 'Fig. 9.' in the bottom center.

RURAL MAIL BOX

Felix Vandevelde, Luxemburg, Wis.

Application August 13, 1936, Serial No. 95,924

2 Claims. (Cl. 232—45)

My invention relates generally to rural mail boxes, and particularly to a mail box of this character involving superiority in structure and operation, whereby the delivery of the mail is facilitated, the mail more completely protected against the weather after delivery, and wherein means is provided for gaining easy access to the interior thereof for removing delivered mail, and an important object of my invention is to provide a simple, practical, and efficient arrangement of the character indicated.

Another important object of my invention is to provide in a mail box structure of the character indicated a novel and superior arrangement and construction of mail flag.

Other important objects of my invention will be apparent from a reading of the following description taken in connection with the drawings, wherein for purposes of illustration I have shown a preferred embodiment of my invention.

In the drawings:—

Figure 1 is a general side elevational view of the embodiment showing the top in closed position.

Figure 2 is a front elevational view of the mail box.

Figure 3 is a transverse vertical sectional view taken through Figure 2 and showing the cover in open position in dotted lines.

Figure 4 is an elevational view of the mail flag.

Figure 5 is a horizontal sectional view taken through Figure 2 and looking downwardly into the interior of the mail box.

Figure 6 is a perspective view of the operating yoke for operating the cover.

Figure 7 is a group perspective view of the parts forming the mail flag.

Figure 8 is a perspective view of the mail flag mounting tube.

Figure 9 is a perspective view of the coin receiving cup.

Figure 10 is a longitudinal sectional view showing in detail the mounting of the mail flag on the cover of the mail box.

Referring in detail to the drawings, the numeral 5 generally designates the mail box which is supported at a suitable height above the ground upon a suitable pedestal 6 which is fixed in the ground or attached to some other adequate support.

The mail box per se comprises the rectangular casing 7 which includes the relatively heavy bottom 8 which is traversed by the mounting bolt or screw 9 which is screwed into the top of the

pedestal or post 6 as indicated in Figure 3. At one side of the bottom near one end of the casing is the coin receiving cup 10. The front wall 11 has therein an opening 12 in which a door 13, hinged at its lower end as indicated by the numeral 14 on the lower side of the opening, is mounted in conjunction with a spring hand retractile flange 15 which has a keeper 16 mounted on the wall 11 above the upper side of the opening 12, to provide easy access into the interior of the casing. A curved apron 17 fastened as indicated by the numeral 18 to the bottom 8 has its upper end located just below the lower edge of the opening 12 as shown in Figures 3 and 5.

The upper edges of the walls 11 and 19 are beveled or slightly curved as indicated by the numerals 20 and 21 to slidably mount the arcuate cross section cover which is generally designated 22 and which is preferably formed of metal including depending flanges 23 on its opposite ends for loose sliding engagement with the end walls of the casing 7.

At each end of the casing 7 is a pivot 24 on which are pivoted the lower ends of the arms 25 and 26 which have their upper ends connected as indicated by the numerals 27 and 28, respectively, to the corresponding flange 23 at spaced points thereof, so as to form a suitable mounting enabling swinging the cover 22 into and out of the open and closed positions illustrated in Figure 3.

A combined operating yoke and retainer 29 shown in detail in Figure 6 comprises the bight portion 30 which has the reduced upper side 31 approximately the width of the front of the casing 7, and the arms 32 and 33 which are formed at their outer ends to receive the respective pivots 28, 28. The arms 32 and 33 are of such a length that while the cover 22 is in the closed position the bight portion 30 will underlie the front edge of the casing as illustrated in Figure 3 whereby the cover is positively held in closed position. Swinging the bight forwardly from the position shown in Figures 1 and 3 will free the operating member so that it may be swung farther upwardly into the position illustrated in dotted lines in Figure 3, wherein the cover 22 will be in the fully opened position. In this fully opened position the bight portion of the operating member will engage the front wall 11 of the casing and prevent the cover from swinging too far rearwardly. To close the cover from the fully opened position it is only necessary to move the operating member forwardly and then downwardly and into the locking position mentioned.

The mail flag which is generally designated 34 comprises the pennant 35 which is riveted or otherwise suitably secured as indicated by the numeral 36 to one side of the mast section 37, and the said mast section 37 has a cut away portion 38 which is complementary to a cut away portion 39 on the lower mast section 40. The lower mast section 40 has a flattened part 41 provided with bolt or screw receiving holes 42 which receive the screws or bolts 43 for fastening the part 41 to the outer side of the corresponding flange 23 of the cover 22. The flattened part 41 has a vertical extension 44 arranged to be received in the slot 45 in the assembling tube 46 which is given a frictional fit on the rounded portions of the mast sections. A pivot 47 traverses the holes 48 and 49 in the lower and upper ends of the mast sections 40 and 37 to pivot the reduced portions thereof together so that the pennant 35 may be raised to the upper position illustrated in the drawings or depressed to the inoperative position; while the tube 46 is in the depressed position in which it is shown in Figure 4. However, when this sleeve or tube 46 is in the elevated position illustrated in Figures 3 and 1, it covers the joint formed by the pivot 47 and keeps the pennant erect in the operative position. In order to keep the tube 46 in the elevated operative position it is raised so that the slot 45 disengages from the projection 44 whereupon the tube is turned around to the position illustrated in Figures 3 and 1 wherein the lower edge of the sleeve is engaged by the upper end of the projection 44.

Although I have shown and described herein a preferred embodiment of my invention, it is to be definitely understood that I do not desire to

limit the application of the invention thereto, and any change or changes may be made in the materials, and in the structure and arrangement of the parts, within the spirit of the invention and the scope of the subjoined claims.

What is claimed is:—

1. A mail box of the character described comprising a casing adapted for mounting on a pedestal or the like and having an apertured arcuate portion, a cover on said casing and conforming to said arcuate portion, means mounting said cover for swinging on a horizontal axis through an eccentric arc relative to the top of the casing, operating means, operatively connected with said cover for swinging said cover from open to closed position and vice versa, said operating means including a retaining portion for engaging a part of the casing to hold the cover in either an open or a closed position.

2. A mail box of the character described comprising a casing adapted for mounting on a pedestal or the like and having an apertured arcuate top portion, an arcuate cover slidably engaged with said arcuate portion for movement from and to a position over the aperture to open and close the latter, means pivotally mounting said cover for swinging on a horizontal axis through an eccentric arc relative to the top of the casing, operating means operatively connected with said cover for swinging said cover from open to closed position and vice versa, said operating means including a retaining portion for engaging a part of the casing to hold the cover in either an open or a closed position, and a mail flag mounted on said cover.

FELIX VANDEVELDE.
